UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 34,430, dated April 23, 1901.

Application filed April 2, 1901. Serial No. 54,094. Term of patent 7 years.

To all whom it may concern:

Be it known that I, WILLIAM T. SMITH, a citizen of the United States, residing in Philadelphia, Pennsylvania, have invented and produced a new and original Design for a Woven Fabric, of which the following is a specification.

My design for a woven fabric is fully shown in the accompanying drawing.

The essential feature of the design is the representation of a stretched skin or hide of a wild animal upon which is the representation of the head of an Indian wearing a feather head-dress. In the design as shown these representations are surrounded by others, such as wigwams, a camp-fire, a bow and ar-

row, a tomahawk, a pipe, a lance or spear, and a coiled snake, and the design has a fringe or border, but the essential feature of the design is as stated.

Having thus described my design, I claim and desire to secure by Letters Patent—

The design for a woven fabric substantially as described and as shown in the accompanying drawing.

In testimony whereof I have signed my name to this specification in the presence of two subscribing witnesses.

W. T. SMITH.
